CLAIM

The ornamental design for a mobile device mount, as shown and described.

DESCRIPTION

FIG. 1 is a front perspective view of a mobile device mount in accordance with the present design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof, but shown in an alternate position; and,

FIG. 9 is a front view thereof.

The broken lines represent unclaimed portions of the claimed design and are included for illustrative purposes only and form no part of the claimed design. The shading represents contour of the claimed design.

1 Claim, 9 Drawing Sheets
